UNITED STATES PATENT OFFICE.

JAMES A. DAVIES, OF SWISSVALE, PENNSYLVANIA, ASSIGNOR TO WESTINGHOUSE ELECTRIC & MANUFACTURING COMPANY, A CORPORATION OF PENNSYLVANIA.

CONTROL MECHANISM FOR COMPOUND TURBINES.

1,302,639.

Specification of Letters Patent.

Patented May 6, 1919.

Application filed July 17, 1916. Serial No. 109,695.

To all whom it may concern:

Be it known that I, JAMES A. DAVIES, a subject of the King of Great Britain and Ireland and a resident of Swissvale, in the county of Allegheny and State of Pennsylvania, have made a new and useful Invention in Control Mechanism for Compound Turbines, of which the following is a specification.

10 This invention relates to compound engines or turbines and particularly to valve mechanisms for controlling the delivery of motive fluid to both the high and low pressure sections of the engine.

15 In marine turbine installations it is common practice to divide the turbine unit into two sections, one of which is termed the high pressure section and receives high pressure steam and the other of which normally

20 receives low pressure steam discharged from the high pressure section. It is sometimes desirable to operate both sections independently and therefore to deliver high pressure steam to the section which normally receives

25 low pressure steam. It is therefore customary to provide a separate maneuvering valve for both the high pressure and the low pressure sections of the turbine unit, and to so arrange the fluid passages that high pressure steam may be delivered simultaneously to both sections of the turbine. In order to deliver high pressure steam to the low pressure section, while the high pressure section is also receiving steam, it is necessary to

30 provide means for shutting off communication between the two sections and for establishing direct communication between the high pressure section and the exhaust passages.

35 An object of my present invention is to provide a simple valve mechanism for closing off communication between the two sections and for establishing direct communication between the high pressure section and the exhaust passages.

40 A further object is to provide new and improved means for insuring that the high pressure section is placed in communication with the exhaust passages or condenser before high pressure steam is delivered to the low pressure section.

45 These and other objects, which will be made apparent throughout the further de-

scription of my invention, are accomplished by means of apparatus embodying features 55 herein described and illustrated.

In the drawings accompanying and forming a part hereof:

Figure 1 a diagrammatic plan view of a cross compound turbine equipped with valve 60 mechanism embodying my invention.

Fig. 2 is a vertical sectional view of a valve, forming a detail of the present invention and adapted to either establish communication between working elements of the 65 high pressure and low pressure sections or establish communication between the high pressure section and the exhaust.

Fig. 3 is a more or less diagrammatic view illustrating an interlocking mechanism 70 forming a part of the present invention; and

Fig. 4 is an elevation of a portion of the apparatus shown in Fig. 3.

Fig. 5 is a view along the line A—A of 75 Fig. 1.

Referring to the drawings: The turbine illustrated consists of a high pressure section 4 and a low pressure section 5. The high pressure section is provided with 80 ahead working elements 4^a, which receive motive fluid or steam from any suitable source of supply through a pipe or passage 6. The section 4 is also provided with reversing elements 4^b which receive steam 85 through a pipe or passage 7. As shown, the ahead and astern elements 4^a and 4^b are separated by a partition wall 4^c. The section 5, like the section 4, is provided with ahead and reversing working elements 5^a 90 and 5^b respectively, the former of which normally receive motive fluid discharged from the ahead elements of the section 4, whereas the latter normally receive fluid discharged from the reversing elements of 95 the section 4. For this reason, the high pressure section 4 is provided with two exhaust ports, one of which communicates through piping 8, valve 9, and piping 8' with the inlet port of the section 5 serving the ahead elements of that section. As shown, one of these exhaust ports is on each side of the partition wall 4^c. The other exhaust port of the section 4 serves the reversing elements of that section and communicates, through piping 10, valve 11 and pip-

ing 10', with the inlet port of the section 5 serving the reversing elements of that section.

Under normal operating conditions steam 5 is delivered to either the ahead or astern working elements 4^a or 4^b of the section 4 by means of a maneuvering valve 12, which may be of ordinary construction. The 10 steam, after traversing one or the other sets of working elements of the section 4, is discharged through the exhaust port, serving those elements, and is delivered to the corresponding working elements of the section 5. For example, while the turbine unit 15 is running ahead, steam is delivered through the pipe 6 to the ahead elements of the section 4 and, after having traversed those elements, is delivered through the pipe 8, valve 9 and pipe 8' to the ahead elements of the 20 section 5. While the turbine unit is reversing, steam is delivered to the reversing elements of the section 4, from which it is delivered through the pipe 10, valve 11 and pipe 10' to the reversing elements of the 25 section 5. The section 5 is shown provided with a single exhaust port 13, which may communicate with a condenser.

When it is desired to operate the section 5 independently of the section 4, means must 30 be employed for placing the section 4 in direct communication with the exhaust and for cutting off communication between it and the working passages of the section 5. The valves 9 and 11 constitute this means, the 35 former controlling communication between the ahead elements of both sections and the latter controlling communication between the reversing elements of both sections. Inasmuch as these valves may be of similar 40 construction, I have only illustrated the details of construction of the valve 9.

Referring to Fig. 2: The valve, as illustrated, includes a casing 14, and a double throw valve disk 15. The casing is provided 45 with a single inlet port 16 and two delivery ports 17 and 18. The valve disk 15 is so arranged within the casing that it is capable of establishing communication between the ports 16 and 18 and of simultaneously cutting off communication between the ports 16 and 17; or of establishing communication between the ports 16 and 17 and of simultaneously cutting off communication between the ports 16 and 18.

55 Referring again to Fig. 1, but in connection with Fig. 2; the port 16 of the valve communicates with the piping 8, whereas the port 17 communicates with the piping 8'. For the sake of clearance the port 17 has been 60 revolved through a 90 degree angle in Fig. 2, and consequently Fig. 2 does not correspond exactly to the diagrammatic illustration of the valve shown in Fig. 1 and Fig. 5. When the valve is in the position illustrated in 65 Fig. 2, steam discharged from the ahead

elements of the high pressure section 4 is delivered through the valve to the ahead elements of the low pressure section 5. When the valve disk 15 is moved to shut off communication between the ports 16 and 17 70 and to establish communication between the ports 16 and 18, steam is delivered from the high pressure section, through the pipe 8, the valve 9 and piping 20, to the exhaust chamber of the section 5, it being understood 75 that this chamber communicates directly with the exhaust port 13 of the section 5 and that therefore steam discharged from the section 4 is bypassed around the working elements of the section 5 and is delivered 80 directly to the exhaust of the turbine or to the condenser serving the turbine. It will also be understood that the piping 20 communicates with the port 18 of the valve casing 14.

85 The corresponding port of the valve 11 communicates with piping 21, which also communicates with the discharge chamber of the section 5 and consequently with the discharge port 13.

90 Referring again to Fig. 2, it will be seen that I have provided a fluid actuated plunger 22 on the valve stem 23 of the valve disk 15 and that this plunger is normally held by a spring 24 in the position in which communication is established between the ports 16 and 17. The plunger 22 is illustrated as located within a cylinder 25, which is adapted to receive actuating fluid through a port 26 and piping 27, the port 26 being so located 95 that fluid, introduced into the cylinder through it, operates to move the plunger 22 in opposition to the pressure of the spring 24 and to establish communication between the ports 16 and 18. As illustrated, the 100 valve stem 23 is provided with an extension 28 which projects beyond a cylinder head 29, with which the cylinder 25 is provided. This extension is provided with an operating 105 lever 30, which may be employed to control the operation of the valve, independently of the fluid actuated plunger, and which also performs the function of a sight indicator 110 since it indicates the position of the valve disk 15.

115 Both the valves 9 and 11 are provided with an actuating plunger 22 and, as illustrated in Fig. 1, the port 26 of the valve 9 receives actuating fluid through the piping 27, whereas the corresponding port of the valve 11 receives actuating fluid through a branch pipe 27', which is in open communication with the pipe 27. With this arrangement, the two valves will operate simultaneously, 120 since actuating fluid will be delivered simultaneously to the actuating plunger of both 125 of them.

130 In Fig. 3, I have illustrated a valve 32, which is adapted to control the delivery of actuating fluid to the piping 27, and conse-

quently to the cylinders 25 of both of the valves 9 and 11. As shown, the valve 32 consists of a casing 33 and a valve disk 34, which is adapted to normally close communication between an inlet port 35 and a delivery port 36 with which the casing 33 is provided. The port 35 communicates with any source of fluid under pressure, such for example, as a steam main or a source of oil pressure and the port 36 communicates with the piping 27. The valve disk as shown is normally held to its seat by a closing spring 37 and is provided with a valve stem 38, which projects through the casing 33. In order to open the valve 32 and to deliver actuating fluid to the piping 27, I have provided a pivoted lever 39, which is adapted to be lifted into locking engagement with a latch 40, shown in Fig. 3, in which position it engages the stem 38 and opens the valve, thereby delivering actuating fluid to the actuating plunger of both the valves 9 and 11 and causing those valves to cut off communication between the working passages of the sections 4 and 5 and to establish direct communication between the section 4 and the exhaust.

In Fig. 1, I have illustrated a maneuvering valve mechanism 42, which is adapted to control the delivery of high pressure steam to the section 5. As shown, the maneuvering valve mechanism 42 receives motive fluid from the steam line 43, and in effect, consists of two valves 42^a and 42^b. The valve 42^a is adapted to deliver high pressure steam through a pipe or passage 44 to the inlet port serving the ahead elements of the section 5. The valve 42^b is adapted to deliver high pressure fluid through a pipe or passage 45 to the inlet port serving the reversing elements of the section 5. As illustrated, both of these valves are of the ordinary construction and each is provided with a hand wheel for operating it.

Inasmuch as it is necessary to close off direct communication between the section 4 and the section 5 and to place the element 4 in communication with the exhaust before delivering high pressure fluid to one or the other sets of working elements of the section 5, it is desirable to provide means for insuring that the changeover valves 9 and 11 accomplish this prior to the delivery of high pressure steam to either the ahead or reverse working elements of the section 5. For this reason I have provided an interlocking mechanism between the operating wheels 46 and 47 and the actuating mechanism of the controlling valve 32, of the valves 9 and 11.

As shown in Figs. 3 and 4, the hand wheels 46 and 47 of the respective valves 42^a and 42^b are each provided with a concentric gear or annular rack 48, which is rigidly mounted on the wheel or on the valve stem of the corresponding valve. The actuating lever 39 of

the valve 32 is shown provided with an interlocking bar 49 which is adapted to be locked into engagement with the rack 48, of both the hand wheels 46 and 47 for the purpose of locking them in the valve closing position 70 when the lever 39 is lowered out of engagement with the valve stem 38. The bar 49 also performs the function of holding the lever 39 in an operative position with relation to the stem 38 of the valve 32, since it 75 is adapted to engage the latch keeper 40.

As shown in the drawings, the bar 49 extends through a slot 50 provided in the lever 39, and is engaged by a pin 51, which is movable longitudinally of the lever for the 80 purpose of varying the position of the bar 49. The bar 49 is forced outwardly, against the pin 51, by a spring 52, which bears upon a collar 53 formed on the lever. As illustrated in Fig. 4, I have provided a finger 85 lever 54 for moving the pin 51 and consequently the bar 49 in opposition to the pressure of the spring. The lever 54 is pivotally mounted on a lug 55 of the lever 39 and, projecting into a recess formed within 90 the lever, engages the pin 51. With this arrangement the bar 49 can be readily shifted for the purpose of disengaging the racks 48 or the latch keeper 40.

With apparatus constructed as in Fig. 95 3, the lever 39 will drop by gravity, when disengaged from the keeper 40 and its bar 49 will then engage the racks 48. It will be apparent that the engine man cannot open either of the valves 42^a or 42^b without first 100 disengaging the lever 39 from the racks 48. In addition to this, the lever must be locked into engagement with the keeper 40 or it will drop down and hamper the operation of opening one or the other of the valves 42^a 105 or 42^b. As soon as the lever 39 is raised and latched into engagement with the keeper, the change over valves 9 and 11 immediately establish communication between the section 4 and the exhaust and cut off communication 110 between the working passages of that section and the working passages of the section 5.

While I have described what I now consider the preferred embodiment of my invention, I desire it to be understood that various changes, modifications, additions, omissions and substitutions may be made in the apparatus illustrated without departing from the spirit and scope of the invention 120 as set forth by the appended claims.

What I claim is:

1. In combination with a turbine divided into a high pressure section and a low pressure section, each provided with an ahead 125 and a reversing element, a valve mechanism for controlling the delivery of fluid to the high pressure section, a valve receiving fluid from the ahead element of the high pressure section and adapted to deliver the fluid so 130

- received to the ahead element of the low pressure section or to the exhaust, a valve for receiving fluid exhausted from the reversing element of the high pressure section 5 and adapted to deliver the fluid so received to the exhaust or to the reversing element of the low pressure section, a valve mechanism for delivering high pressure fluid to the elements of the low pressure section, and pressure controlled means for actuating both of said before mentioned valves to close off communication between said sections and for establishing communication between the high pressure section and the exhaust.
- 15 2. In combination with a turbine divided into a high pressure section and a low pressure section, each provided with an ahead and a reversing element, a valve mechanism for controlling the delivery of fluid to the high pressure section, a valve receiving fluid from the ahead element of the high pressure section and adapted to deliver the fluid so received to the ahead element of the low pressure section or to the exhaust, a valve 20 for receiving fluid exhausted from the reversing element of the high pressure section and adapted to deliver the fluid so received to the exhaust or to the reversing element of the low pressure section, a valve mechanism 25 for delivering high pressure fluid to the elements of the low pressure section, pressure actuated means for actuating both of said before mentioned valves to close off communication between said sections and for establishing communication between the high pressure section and the exhaust, and an interlocking mechanism for holding said last mentioned valve mechanism closed and for controlling the delivery of actuating fluid 30 to said means.
3. In combination with a compound engine having a high pressure section and a low pressure section, a valve for establishing communication between said sections or between the high pressure section and the exhaust, controlling means therefor, a valve mechanism for delivering high pressure steam to the low pressure section, and interlocking means for said last mentioned valve 45 for controlling the operation of said first mentioned valve, said interlocking means including a member which falls into locking engagement with the last mentioned valve when not in engagement with the controlling means of the first mentioned valve.
- 50 4. In combination with a compound engine having a high pressure section and a low pressure section, a valve for establishing communication between said sections or between the high pressure section and the exhaust, pressure actuated means for controlling the operation of said valve, a valve for delivering high pressure motive fluid to said low pressure section, and means interlocking 55 with said last mentioned means for controlling the operation of said pressure actuated means.
5. In combination with a compound engine having a high pressure section and a low pressure section, a valve for establishing communication between said sections or between the high pressure section and the exhaust, controlling means therefor, a valve mechanism for delivering high pressure steam to the low pressure section, means interlocking with said valve mechanism for actuating said first mentioned valve to establish communication between said high pressure section of the engine, and the exhaust when moved out of interlocking engagement with said valve mechanism, said interlocking means including an interlocking member which automatically moves into locking engagement with the valve mechanism when not in engagement with the controlling means of the first mentioned valve.
6. In combination with a compound engine having a high pressure section and a low pressure section, a valve for establishing communication between said sections or between the high pressure section and the exhaust, pressure actuated means for controlling the operation of said valve, a valve mechanism for delivering high pressure steam to the low pressure section of the engine, means interlocking with said mechanism for controlling the operation of said pressure actuated means to actuate the valve to shut off communication between the sections and to establish communication between the high pressure section and the exhaust when moved out of interlocking engagement with said valve mechanism.
7. In combination with a compound engine having a high pressure section and a low pressure section, a valve for establishing communication between said sections or between the high pressure section and the exhaust, pressure actuated means for controlling the operation of said valve, a delivery valve for controlling the delivery of actuating fluid to and from said means, a valve for delivering high pressure motive fluid to said low pressure section, and a movable interlocking member for opening the delivery valve and simultaneously releasing the last mentioned valve when in one position and for allowing the delivery valve to close and to lock the last mentioned valve in a closed position when said member is in another position.
8. In combination with a turbine having a high pressure section and a low pressure section, a valve for delivering steam from the high pressure section to the low pressure section when in one position and to the exhaust when in another position, a plunger responsive to fluid pressure for controlling said valve, a valve for delivering high pressure steam to the low pressure section, a de-

livery valve adjacent thereto for controlling the delivery of actuating fluid to and from the plunger of the first mentioned valve, and an interlocking member for releasing the 5 high pressure valve and for opening the delivery valve in one position, and for locking the high pressure valve and for closing the delivery valve in another position, said member being arranged to automatically move 10 from one position to the other when released.

9. In combination with a turbine divided into a high pressure section and a low pressure section, each provided with an ahead and a reversing element, a valve mechanism 15 for controlling the delivery of fluid to the high pressure section, a valve receiving fluid from the ahead element of the high pressure section and adapted to deliver the fluid so received to the ahead element 20 of the low pressure section or to the exhaust, a valve for receiving fluid exhausted from the reversing element of the high pressure section and adapted to deliver the fluid so received to the exhaust or to the reversing 25 element of the low pressure section, means for controlling both of said valves, a valve mechanism for delivering high pressure fluid to the elements of the low pressure section and an actuating means for the controller adapted to be moved into and out of operative relation with the controlling means and when out of operative position to lock the last mentioned valve mechanism.

10. In combination with a turbine divided 30 into a high pressure section and a low pressure section, each provided with an ahead and a reversing element, a valve mechanism for controlling the delivering of fluid to the high pressure section, a second valve mechanism for delivering high pressure fluid to the elements of the low pressure section, a valve receiving fluid from the ahead element of the high pressure section and adapted to deliver the fluid so received to the ahead 35 element of the low pressure section or to the

exhaust, a valve for receiving fluid exhausted from the reversing element of the high pressure section and adapted to deliver the fluid so received to the reversing element of the low pressure section or to the exhaust, means normally holding the said valves so as to cut off communication between the high pressure section and the exhaust, actuating means for moving the said valves so as to close communication between 50 the said sections and open the high pressure section to the exhaust, and means for controlling the last mentioned means adapted, when out of operative relation therewith, to lock the second valve mechanism in closed 55 position, and when in operative relation to permit the opening of the second valve mechanism.

11. In combination with a turbine divided into a high pressure section and a low pressure section, each provided with an ahead and a reversing element, a valve mechanism for controlling the delivery of fluid to the high pressure section, a valve receiving fluid from the ahead element of the high pressure 60 section and adapted to deliver the fluid so received to the ahead element of the low pressure section or to the exhaust, a valve for receiving fluid exhausted from the reversing element of the high pressure section and adapted to deliver the fluid so received to the exhaust or to the reversing element of the low pressure section, a means for delivering high pressure fluid to the elements of the low pressure section, means for actuating 65 the before mentioned valves, means for controlling the said actuating means, and means coöperating therewith for holding the pressure delivering means inoperative when the said valves are delivering high pressure 70 fluid to the low pressure section.

In testimony whereof, I have hereunto subscribed my name this 15th day of July, 1916.

JAMES A. DAVIES.
